CLAIM

The ornamental design for a shrouded microwave antenna reflector, as shown and described.

DESCRIPTION

1. Shrouded microwave antenna reflector

1.1 : Front perspective

1.2 : Side perspective

1.3 : Front

1.4 : Back

1.5 : Top

1.6 : Bottom

1.7 : Left

1.8 : Right

The broken lines lines depict portions of the antenna reflector and environment, which form no part of the claimed design.

1 Claim, 8 Drawing Sheets
